(57) **CLAIM**

What is claimed is the ornamental design for a combination electronic accessory box and mounting base, as shown and described herein.

DESCRIPTION

FIG. 1 is a perspective view of the electronic accessory box in accordance with our invention;

FIG. 2 is a front view of the accessory box thereof;

FIG. 3 is a side view of the accessory box thereof;

FIG. 4 is an opposing side view of the accessory box thereof;

FIG. 5 is a top view of the accessory box thereof;

FIG. 6 is a bottom view of the accessory box thereof;

FIG. 7 is a perspective view of the mounting base in accordance with our invention;

FIG. 8 is a side view of the mounting base thereof;

FIG. 9 is a top view of the mounting base thereof;

FIG. 10 is a front view of the extender base thereof; and,

FIG. 11 is a top view of the combination electronic accessory box & mounting base of our invention as shown.
